DISHWASHING MACHINE

Edgar S. Stoddard, Berwyn, and Willard C. Rykert, Hinsdale, Ill., assignors to The Conover Company, Chicago, Ill., a corporation of Illinois

Application April 24, 1930, Serial No. 446,809

4 Claims. (Cl. 299—63)

The present invention relates to impellers for agitating, spraying and moving liquids, and it particularly relates to impellers for use in the spray-projection type of dishwashing machines.

In these spray-projection machines, more fully described in copending application Serial No. 389,696 filed August 31, 1929, now Letters Patent No. 1,937,100 issued November 28, 1933, it is desirable to utilize a small amount of cleansing liquid and to throw the cleansing liquid tangentially upwardly and outwardly from a low level toward, and upon, dishes and similar objects at a high velocity. The dishes at all times are substantially above the level of the pool of cleansing liquid in the bottom of the machine and the cleansing action is exclusively due to the action of a projected or reflected spray. It is desirable to project the liquid spray at such velocity that it will have a force sufficient to remove the adherent dirt from the surfaces of the dishes and other objects.

An object of this invention is to provide an improved impeller for spraying liquids which is particularly adapted to be utilized in a spray-projection type of washing machine.

Another object of this invention is to provide an impeller which may be centrally positioned and which will cooperate with a centrally located drain-level device.

A further object of the present invention is to provide in combination with a spray-projection dishwashing machine impeller, suitable apparatus for directing the flow of the liquid being supplied to the impeller and also the course of the liquid being projected by said impeller.

Other objects will appear during the course of the following description.

The following drawings represent several embodiments of the invention, to which the invention, however, is by no means restricted:

Fig. 1 represents a vertical sectional view of a dishwashing machine with the impeller in position;

Figs. 2, 3 and 4 represent enlarged side and top views of the embodiment of the impeller shown in Fig. 1; and

Fig. 5 shows the driving connections of the impeller and the cooperating centrifugal in section illustrating their positions and attachments.

In Fig. 1 the tank of the dishwashing machine 11 is provided with a removable cover 12. The impeller 34 is disposed centrally in the lower portion of the tank 11 and is actuated by means of a vertical shaft which extends through the bottom of the tank (see Fig. 5).

In the tank 11 are positioned the dish racks 31 of any suitable construction. These racks are intended to support dishes or similar objects in the washing chamber substantially above the impeller and above the pool level. The dishes or other similar objects are so supported by means of the rack 31 that the liquid spray-projected by the impeller will contact with them at such an angle as to cleanse them most effectually. The normal static water level is approximately indicated at 32. It will be noted that the normal static water level is regulated so that the impeller 34 is only partially immersed. The dynamic water level usually will be materially lower than the static water level because a substantial amount of liquid will be in the course of being spray-projected into the washing chamber and will also be retained upon the rack structure or the objects being cleansed.

The water-propelling or circulating device 34 is positioned in the lower central part of the tank and is so designed as to elevate small sheets or streams of water from the pool in the lower portion of the vessel at, or closely adjacent, the central axis of the machine, through a comparatively small compass to a point slightly above the pool level. Such elevated streams of water are thrown upwardly and outwardly from such elevated point at a high rotational velocity in intermittent or continuous streams and/or sheets.

The impeller, shown in Fig. 1 and more fully in Figs. 2 to 4 comprises a head 35 which is attached to the top of the motor shaft and two elevating and projecting blades 36 and 37. The head 35 (see Figs. 2, 3 and 4) has a central conical portion 20 and is provided with outwardly projecting fins 21 which support the upper ends of the blades 36 and 37. These fins are so proportioned and positioned that the line of joinder 30 between the blades 36 and 37 and the fins 21 will slope inwardly and downwardly until they reach the bottom of the conical portion 20. The line 30 should reach the bottom at a point of the conical portion 20 in advance of a point directly under the upper outer point 23 of the fin 21 in the direction of rotation.

The head piece 35 primarily serves as a supporting member designed to attach the rotating blades to the top of the driving or motor shaft. It may be made cylindrical or of other shape than that shown. It is desirable to attach the blades to the head piece in such manner that the surface of the blade will blend into the head piece. In the present embodiment the head piece 35 is so designed as to give maximum strength to the 116

blade attachment and result in minimum interference with the spray projection. The upper surfaces of the fins 21 constitute a continuation of the elevator and projector surfaces and assist 5 in the spray-projection action adjacent the line 30.

The circular inclined or screw surfaces 38 and 39 forming the lower elevating portions of the blades 36 and 37 extend down to a point below 10 the normal surface 32 of the liquid pool contained in the bottom of the washing chamber of the tank 11. The elevator surfaces 38 and 39 terminate in the curved edge 24.

In the present embodiment, both blades 36 and 15 37 are of the same size and shape. As shown (see especially Fig. 4) the inclined surfaces 38 and 39 at the bottom of the blades 36 and 37 terminate within a range about 180 to 270° of the commencement of the deflector on the head 35. 20 In the embodiment shown they preferably extend around the head 35 an angular distance between about 205° and 235°.

The upper portions of the blades at their line of attachment 30 to the head 35 approach the 25 vertical as indicated at 40 (see Fig. 3). The upper substantially vertical surface 40 turns away from the head piece 35 in the direction of rotation. The highest point 23 of the deflector is so positioned that it will be substantially at the top 30 of the line of jointure 30.

The projector and elevator surfaces are so shaped that the traces of vertical radial intersecting planes will be approximately parabolas. The curvature of the parabolas will increase as 35 the top of the cylinder is reached starting with a substantially very slight curvature at the bottom of the blade. The water in ascending the elevator and projector surfaces will not rotate at the same speed as the surfaces themselves, 40 due to its slip. The rotational speed of the liquid body on the impeller blade, however, will increase as the top of the blade is approached, starting from almost zero at the bottom of the blade and increasing to a maximum at the top. The radial 45 trace above described at any place on the surface of the blade should be approximately a parabola of the same shape and value as the parabola which would be formed by the liquid, if rotating in a vessel at the same rotational velocity. The resulting shape of blade will be a modified parabolic 50 surface which at any place will have substantially the same shape and value as the parabolic surface which would be taken by the water upon it, if rotating at the same rotational velocity. 55 This parabolic surface may be modified to produce the necessary directional flow and/or distribution of the cleansing fluids.

Starting from the terminating upper edge of the inclined surface, the radial width of the inclined surface increases so that at the point of about 90° to 180°, approximately 135° in the embodiment shown, horizontally in advance of the vertical terminating plane 40 in the embodiment of the invention shown, the impeller will achieve 60 its maximum width as indicated at 44. From place of maximum width 44, the width of the inclined surface very rapidly decreases until it terminates at the point 45. The amount of this decrease will be governed by the shape, size and 65 pitch of the bottom of the tank and the amount of cleansing fluid used. The inclined surface is so widened and curved that the efficient projection of the spray will not be interfere with by the centrifugal force tending to throw the water 70 off the blade sidewardly.

Both the concavity and the pitch of the elevating and deflecting surfaces may increase as the top of the impeller is approached as in the embodiment shown. The present pitch varies from about 15° to the horizontal at the bottom to 80 about 80° to the horizontal at the top.

In the present embodiment the projector and elevator surfaces of the blades are spaced away from the axis of the impeller by a distance, which may vary between one-fourth and one-half the maximum width of a single blade. This spacing may be uniform from the place of attachment of the blade to its termination.

This proportion may vary so that the distance from the edge 46 to the axis 48 will be between one-fourth and three-fourths of the width of the blade at the place 44. The radial width of the blade at its point of commencement, that is, from the point 22 to the outer edge of the blade, will be about one-half of the radial width of the blade at the point 44. Of course the actual width of the blade will be controlled not only by the radial width but also by the pitch thereof. The maximum radial distance of the outer edge of the blade at the point 44 may preferably be 100 somewhat less than the height of the impeller from the highest point 23 to the lowest point 45, and in the embodiment shown this distance is between $\frac{3}{4}$ and $\frac{7}{8}$ of the height of the impelling device. It has been found satisfactory to vary 105 this height so that it will be between one to two times the maximum radial width 44. It therefore follows that the impeller while rotating will sweep out an elliptical volume which in the embodiment shown will be of greater horizontal dimension.

The impeller in the present embodiment is so proportioned to the tank that the tank diameter will be four to ten or more times the maximum radial distance 44. In the embodiment shown, 115 the tank diameter is approximately seven times the distance from the axis 48 to the outer edge of the blade at the point 44. The impelling device will project upwardly into the washing chamber above the dynamic level of the cleansing fluid a distance which is approximately $\frac{1}{4}$ to $\frac{3}{4}$ of its total height. It preferably should not extend into the well 60. The impeller 34 is adapted to cooperate with the draining bottom, 120 which, it is noted, is formed of a series of frustummed conical portions of increasing inclination to the horizontal. The outer portion of the draining bottom 61 is joined by an intermediate portion 62 of increasing slope, which in turn is 125 finally joined by means of the substantially vertical portion 63. The bottom is finally terminated by the slightly sloping portion 64 which is approximately parallel to the outer portion 61. The conical portions 63 and 64 may be considered to form a well 60 above which the impeller is positioned.

Positioned in the well and over the impeller is an impeller guard device 70 which is fitted into position by means of the circular groove 71 which cooperates with the lower ends 72 of the guard. Attached to the side of the guard are a series of plates 73. These plates 73 serve to direct the water which descends to the impeller over the draining bottom, and they also tend to decrease 140 the amount of whirl in such water as it descends. Attached to the top of the guard 70 are short vertical baffle plates 77 which direct the water projected upwardly by the impeller 34, so that 145 it will more thoroughly cleanse the glasses, cups 150

and other articles placed in the central upper rack structure.

The impeller is driven by a motor shaft 81, which extends upwardly into the well of the tank. At the top of the shaft is a shouldered threaded portion 82 which is screwed into the middle of the conical head 35. This shaft 81 is provided with the bearing 83 which fits into the bottom of a bearing sleeve 85 attached to the top 10 of the motor casing. Surrounding the bearing sleeve 85 is the rotating impeller sleeve 86 which screws onto the threaded portion 87 attached to the bottom of the conical head 35. To the lower end of this rotating sleeve 85 is attached a centrifugal pump 97 which rotates in the lower well chamber 98 and serves to remove waste liquids from the washing chamber into the drain-line 99 (see Fig. 1).

The wings of the impeller are adapted to embrace and extend around a drain-level connection shown in side view in Fig. 1 and in side section in Fig. 5. This drain-level connection is more fully shown and described in a copending application Serial No. 449,186, filed May 2, 1930. Referring to Fig. 5, covering the lower well chamber 98 is the well cover 76 which is centrally provided with an opening to receive the drive shaft 81. Around the periphery of this opening is a rotary valve 92 spaced from the sleeve 86 25 and adapted to be operated by the link rod 104. Openings 93 are provided through the rotary valve. An overflow tube 94 is mounted around the shaft 81 and sleeve 86 and seated on the inner rotary member of the valve 92 forming a watertight seal therewith. The height of this tube should conform to the desired maximum height of the water level in the tank 11. The overflow tube 94 is spaced from the impeller sleeve 86, thus forming a liquid communication from the tank 11 to the well chamber 98 by means of the passageway formed between the overflow tube 40 94 and the impeller sleeve 86.

It is evident that by turning the rod 104 the openings 93 in the valve 92 may be made to cooperate with one another to permit water in the tank 11 to pass directly by gravity from tank 11 through the openings 93 to the well chamber 98. When the rod 104 is oppositely turned, openings 93 are rotated out of alignment and this avenue of escape for the water in tank 11 50 is closed. While this avenue is closed, the only other means of escape is by way of the overflow tube 94, and this means will be operative only when the water level in tank 11 reaches a height 55 equal to the height of the top of the tube.

The impeller blades 36 and 37 extend down and around the overflow tube and, while in operation, prevent any substantial amount of water from passing down the tube because of the circulation set up in the water thereby. To prevent turbulence of the water about the overflow tube, a stationary outer shell 91 is mounted around the overflow tube and between it and the impeller blades. This shell is open at its bottom to permit easy access of the water to the overflow tube, but it is adapted to fit sufficiently close to the overflow tube and the tank bottom that a substantially quiescent body of water is maintained within and beneath the shell.

The operation of the impelling device is as follows: The impeller device will be rapidly ro-

tated by the shaft 81 at a rotational speed of about 1000 to 2500 R. P. M. The lower curved edges 24 will cut into the pool of cleansing and rinsing liquid and will elevate portions of it to the upper more vertical portions of the blades 36 and 37 and spray-project it outwardly and upwardly into the washing chamber. Some of the liquid thus spray-projected will contact with the small baffles 77 and will be reflected more directly into the central upper rack. The returning liquid will flow downwardly and inwardly over the draining bottom 61 into the well 60 and it will be directed into the well by means of the baffles 74. These baffles will serve to decrease any rotational movement it may have.

When the rinsing or cleansing operation is finished, the valve 93 may be turned so as to drain the waste liquids from the well 60 and the washing chamber into the centrifugal chamber 98, from whence they will be exhausted by means of the centrifugal device 97.

This application is a continuation in part of applications Serial Nos. 266,496, filed April 2, 1928, 290,344, filed July 5, 1928 and 344,111, filed March 5, 1929 now Letters Patent No. 1,870,317 issued August 9, 1932.

The foregoing detailed description has been given for clearness of understanding only and no unnecessary limitation should be understood therefrom, but the appended claims should be construed as broadly as permissible in view of the prior art.

What is claimed is:

1. A liquid agitating and impelling device comprising a central conical member, a plurality of fins extending outwardly from said conical member, and outwardly then downwardly extending blades attached to the edges of said fins.

2. A liquid agitating and propelling device comprising a central conical member provided with outwardly extending fins which join at their lower extremities with the conical member and extend upwardly and outwardly a substantial distance from the conical member, and an equal number of outwardly then downwardly extending blades of decreasing pitch attached at their upper ends to the edges of said fins.

3. A spray projecting device comprising a central head member tapped to receive an upwardly extending drive shaft, a pair of fins extending outwardly and upwardly from diametrically opposite sides of said member, which fins adjacent the top of the head member decrease in thickness outwardly until they form an edge, and a pair of elevating and projecting blades the upper ends of which are attached to the edges of the fins of said head member and which first extend outwardly and then downwardly around the axis of said conical member.

4. A spray-projecting impeller, comprising a head member, and outwardly and downwardly extending blades attached thereto, the inner edges of said blades being removed a substantial distance from and extending downwardly around said head member, and said blades having a width which first increases and then decreases, a maximum radial width being reached at about 90° to 180° from the place of attachment of said blades to the head member.
